UNITED STATES PATENT OFFICE

173,070

CARTON SET UP AND CLOSING MACHINE

Al Johnson, Stockton, Calif.

Application October 23, 1952, Serial No. 21,961

Term of patent 14 years

(Cl. D55—1)

To all whom it may concern:

Be it known that I, Al Johnson, a citizen of the United States, residing in the city of Stockton, county of San Joaquin, State of California, have invented a new, original, and ornamental Design for a Carton Set Up and Closing Machine, of which the following is a specification, reference being had to the accompanying drawing, forming a part hereof.

Figure 1 is a front perspective view of the carton set up and closing machine, showing my new design.

Figure 2 is a rear perspective view thereof.

I claim:

The ornamental design for a carton set up and closing machine, substantially as shown.
